UNITED STATES PATENT OFFICE.

CLARENCE O. MARRIS, OF AKRON, OHIO.

GLOBE-HOLDER.

1,037,276.

Specification of Letters Patent. Patented Sept. 3, 1912.

Application filed January 2, 1912. Serial No. 668,846.

To all whom it may concern:

Be it known that I, CLARENCE O. MARRIS, a citizen of the United States, residing at Akron, in the county of Summit and State 5 of Ohio, have invented certain new and useful improvements in Globe-Holders, of which the following is a specification, reference being had to the accompanying drawings.

10 This invention relates to certain new and useful improvements in globe holders and has for its object to provide a device of this character which will securely support or hold the globe or shade upon the burner of 15 a chandelier or gas bracket.

Another object of the invention is to provide a holder for the above purpose which may be easily and quickly operated to secure the globe in position or permit of its detachment from the burner.

20 Still another object of the invention resides in the provision of a simple and effective globe holder constructed from a single length of resilient wire which is so arranged 25 upon the burner as to permit of the expansion of the globe and thereby obviate liability of its breakage while at the same time the globe is securely retained or held in position.

30 With the above and other objects in view, the invention consists of the novel features of construction, combination and arrangement of parts hereinafter fully described and claimed, and illustrated in the accompanying drawings, in which

35 Figure 1 is a side elevation of a gas burner of the inverted type having my improved globe holder applied thereto; Fig. 2 is a section taken on the line 2—2 of Fig. 1; Fig. 40 3 is a bottom plan view of the burner, the globe being removed; and Fig. 4 is a detail perspective view of the holder detached from the burner.

40 Referring in detail to the drawing 5 designates the frame of the burner in which the globe 6 is adapted to be held, said globe being provided upon its upper end with a contracted neck 7 which is formed thereon by the provision of a circumferential channel 8. In the ordinary mode of attachment 45 of the globe to the burner frame, the contracted neck or flange thereon is disposed within the annular wall of the burner frame, and said wall is provided with suitable 50 binding screws which are threaded therein and are adapted to engage in the channel 8

of the globe to securely hold the globe in position. This ordinary holding means for gas globes has been found unsatisfactory because the globe expands under the intense 60 heat and as it is rigidly held by means of the binding screws, the neck or flange thereon breaks, thus allowing the globe to fall. This is quite a frequent occurrence and the main object of my invention is to allow for 65 the expansion of the globe and thus eliminate all liability of its breakage.

In the attainment of the above end, I provide a single length of resilient wire which is bent to form the spaced parallel bowed 70 portions 9 and 10 respectively, said bowed portions of the wire being arranged in opposed relation. These bowed portions 9 and 10 of the wire are connected as indicated at 11. The opposed portions 10 of the wire are disposed upon the inner face of 75 the annular wall of the burner frame and are clamped thereagainst by means of the screws 12 which are provided with hooks upon their inner ends to engage over the 80 wire and have suitable nuts 13 on their outer ends. The connected portions 9 and 10 of the wire holder are slightly spaced and the other ends of the portions 10 of the wire are projected at right angles as indicated at 14, 85 said wire being provided in its intermediate portion with an elongated horizontal loop 15. Through this loop the free ends of the portions 9 of the wires are projected and have 90 eyes 16 formed thereon to provide suitable finger-pieces. It will be observed that the lowermost bowed portions 9 of the wire are disposed below the lower edge of the burner frame. The resiliency of the wire normally holds these bowed portions 9 thereof in their 95 relative contracted positions, wherein the same are disposed inwardly of the annular wall of the burner frame. The loop 15 provides guides for the ends of the bowed portions 9 of the wire as they are forced in opposite directions, the eyes 16 on the ends 100 of the wire being normally disposed in the center of the loop 15.

In the operation of my improved globe holder, the contracted neck or flange 7 of the globe is disposed between the oppositely bowed portions 9 of the wire, said bowed portions of the wire being forced apart by the thumb and forefinger of the operator. Upon the release of pressure upon the ends 110 of the holder, said bowed portions of the wire return to their natural condition and

are received in the channel 8 of the globe and exert sufficient clamping pressure thereon to securely hold the globe in position against liability of its accidental displacement. It will be understood that the contracted neck of the globe does not extend within the annular wall of the burner frame, but the upper edge of said neck is disposed substantially in the same plate as the lower edge of the burner. By means of this construction, it will be readily seen that the globe may be easily and quickly removed by simply forcing the portions 9 of the wire apart, without danger of injury to the incandescent mantle. In the expansion of the globe, the resiliency of the wire holder permits the portions 9 thereof to be forced apart so that the globe will not be broken. It is, however, securely held in place beneath the burner.

Owing to the one-piece construction of my improved holder, the same may be produced at very small cost. It is also extremely durable and highly efficient in practical use and admits of the quick removal of the globe for cleaning purposes.

While I have shown and described the preferred form and construction of the various parts, it will be understood that the invention is susceptible of considerable modification without departing from the essential feature or sacrificing any of the advantages thereof.

Having thus described the invention what is claimed is:—

1. A globe holder of the character described formed from a single length of resilient wire, means to secure said wire to a burner, the ends of said wire being oppositely bowed to provide clamping arms for engagement with the globe, and an elongated loop formed in the intermediate portions of the wire to provide a guide for the free ends of the wire.

2. A globe holder of the character described comprising a single length of resilient wire bent to provide upper and lower oppositely bowed parallel portions, the upper opposed bowed portions of the wire being adapted for attachment to a burner, the lower opposed bowed portions of the wire being relatively movable and adapted for resilient clamping engagement with the

globe, and a guide formed in the wire intermediate of its ends to receive the free ends 55 of the latter bowed portions thereof.

3. A globe holder of the character described comprising a single length of resilient wire having its end portions bent to provide oppositely bowed resilient arms 60 adapted for clamping engagement upon the globe, the intermediate portion of said wire being adapted for attachment to a burner, said wire having a central loop formed therein through which the ends of the 65 bowed portions of the wire are projected to provide a guide therefor.

4. The combination with a burner, of a globe holder formed from a single length of wire and having parallel oppositely 70 bowed portions, means to rigidly and removably secure one of the bowed portions of said wire to the burner, the free opposed bowed portions of the wire being resiliently 75 movable for clamping engagement with the globe, and a guide loop for the ends of said movable portions of the wire.

5. The combination with a burner, of a globe holder formed from a single length of resilient wire bent to provide parallel oppositely bowed portions, means to clamp one of the parallel bowed portions of the wire to the burner wall, said wire being provided with a horizontal elongated loop centrally formed therein, the other parallel 85 bowed portions of the wire being resiliently movable for clamping engagement with the globe and having their other ends projected at right angles and disposed through said loop, the ends of the wire being provided 90 with eyes forming finger-pieces whereby they may be forced apart to release the globe.

6. A globe holder of the character described comprising a wire adapted to be secured to a burner and having a guide loop formed therein, and opposed globe clamping arms having their extremities projected through said loop.

In testimony whereof I hereunto affix my 100 signature in the presence of two witnesses.

CLARENCE O. MARRIS.
